UNITED STATES PATENT OFFICE.

WILLIAM F. HARRAH, OF NILES, MICHIGAN, ASSIGNOR TO AMERICAN WIRE FABRICS COMPANY, OF CLINTON, IOWA, A CORPORATION OF IOWA.

PROCESS OF MAKING NARROW-WIDTH WIRE FLY-SCREEN CLOTH.

1,120,479.

Specification of Letters Patent.

Patented Dec. 8, 1914.

Application filed July 7, 1913. Serial No. 777,727.

To all whom it may concern:

Be it known that I, WILLIAM F. HARRAH, a citizen of the United States, residing at Niles, in the county of Berrien and State of Michigan, have invented a certain new and useful Process of Making Narrow-Width Wire Fly-Screen Cloth; and I do hereby declare the following to be a full, clear, and exact description of the same, 10 reference being had to the accompanying drawings, forming part of this specification, and to the figures and letters of reference marked thereon.

In the manufacture of wire screen cloth commonly designated as fly screen cloth, it is found that the cost of manufacturing narrow widths is practically the same as the cost of manufacturing wide widths, except for the difference in the quantity of the material employed; that is to say, the time and power required are practically the same, and consequently, looms for the weaving of this character of material are ordinarily made of a size to weave cloth of a standard wide width, and when narrow cloth is to be woven, a smaller number of warp wires are employed, the other parts of the mechanism being correspondingly set for the width to be woven.

30 The object of the present invention is to provide a process of manufacture which may be practised without change in the ordinary equipment, but which will result in the production of two or more widths of narrow screen cloth with the expenditure of no greater time or power than in the production of single narrow widths, and without requiring readjustment or setting of the parts of the mechanism different from 35 the adjustment or setting employed in the manufacture of wide widths.

To the above ends, the invention consists, broadly stated, in weaving the fly screen cloth in a single width which is equal to 45 the combined widths of a plurality of the desired narrow widths, and with spaced internal or inner selvages each formed by warp wires which are woven close together so as to grip the weft wires on opposite sides 50 in substantially the same plane, then applying a coating to cause the selvage warp and the weft wires to adhere to each other, and finally severing the cloth into the desired narrow widths by cutting the weft wires in 55 the space between the selvages and winding

the narrow widths separately from each other.

Referring to the accompanying drawings,—Figure 1 is a perspective view diagrammatic in character, of a section of wire fly screen cloth illustrating the process of manufacture. Fig. 2 is a diagrammatic illustration of the mechanism preferably employed in the manufacture of the cloth.

Wire screen cloth of the character referred to is formed by warp and weft wires which are spaced apart a distance to form openings of the desired size, and in accordance with the process of the present invention, a sufficient number of warp wires are employed to form a cloth which will be in width equal to a plurality of the narrow width desired. As illustrated in the drawing, the cloth is woven double the width desired and, while one integral width, is subjected to the coating and drying steps of the process. In Fig. 1, the portion of the cloth at A is supposed to be that portion which is delivered from the weaving loom, and it will be noted that at the center or middle portion, spaced selvages are formed by bringing two warp wires close together on each side of a center space, the two selvage warp wires being indicated by a , in one width, and a' in the other width. These selvage warp wires for each selvage are usually and conveniently placed in the same space between the reed splits, there being a single space left unoccupied in the reed between the two selvages. With this manipulation the selvage warp wires grip the weft wires on opposite sides and in substantially the same plane, but with wire cloth, a severing of the two narrow widths at this stage would be impractical, because of the likelihood of the warp wires slipping on the weft wires and resulting in an imperfect product. To prevent this result, the screen cloth is coated with a coating which will at the same time protect the wire and also serve as a means to cause the warp selvage wires and the weft wires to adhere to each other, this stage of the process being indicated in the drawing at B.

This coating is dried as indicated at C, and finally the narrow widths are separated by severing the weft wires in the space between the inner selvages, as at D, for which purpose rotary cutters d , Fig. 2, may be employed, and immediately thereafter, the

two narrow widths are separately rolled, as at E, and prepared for the market.

The narrow widths of screen cloth prepared as described in accordance with this invention have the inner ends of the weft wires so held that not only will any transverse bending of said ends be in a uniform line longitudinally of the cloth, regardless of the direction of the bend, but the warp wires forming the selvages are firmly gripped and connected with the weft wires at points slightly removed from their ends. Practice demonstrates that the selvage thus formed is of sufficient strength to prevent the raveling of the edge under all ordinary conditions and use. The edge furthermore, is stiffened and will be more firmly held in line, as for example, where tacked into screens with the tacks spaced a considerable distance apart.

In the manufacture of narrow width fly screen cloth in accordance with this invention no change in the ordinary equipment is required, save the introduction of the cutters in such position or relation to the other parts of the plant that the cloth may be split into the narrow widths, after the coating and drying stages of the operation, and preliminary to the winding of the widths into rolls.

Practice demonstrates that the process results in a very material saving to the manufacturer, the only additional material required being one extra warp wire which is introduced to form one of the selvage wires on one side of the space, the wire which would normally occupy said space being moved over to form the extra or selvage warp wire of the other width. Obviously more than two narrow widths with separating selvages may be woven at one time and the narrow widths may be of equal or unequal width as desired.

Having thus described my invention, what I claim as new and desire to secure by Letters Patent of the United States is,

1. The improved process of making narrow width wire fly screen cloth, which consists in weaving the screen cloth in a single web substantially equal in width to the combined widths of a plurality of the desired narrow widths, and with spaced inner selvages separating the web into the narrow widths, said selvages being formed by warp wires woven close together to grip the weft wires on opposite sides in substantially the same plane, then applying a coating to cause the selvage warp and weft wires to adhere to each other, and finally severing the cloth into the desired widths by cutting the weft wires in the space between the selvages formed by the closely woven warp wires.

2. The improved process of making narrow width wire fly screen cloth, which consists in weaving the screen cloth in a single web substantially equal in width to the combined widths of a plurality of the desired narrow widths, omitting a warp wire to form the space between the narrow widths, introducing additional warp wires on each side of said space to form selvages which grip the weft wires on opposite sides in substantially the same plane, then applying a coating to cause the selvage warp and the weft wires to adhere to each other, then drying said coating, then severing the cloth into the desired narrow widths, by cutting the weft wires in the space between the selvages from which the warp wire was omitted, and finally winding the narrow widths separately from each other.

WILLIAM F. HARRAH.
